UNITED STATES PATENT OFFICE

116,841

DESIGN FOR A FIRE TRUCK

James W. Fitch, Seattle, Wash., assignor to Kenworth Motor Truck Corporation, Seattle, Wash., a corporation of Washington

Application March 22, 1939, Serial No. 83,778

Term of patent 7 years

To all whom it may concern:

Be it known that I, James W. Fitch, a citizen of the United States, residing at Seattle, in the county of King and State of Washington, have invented a new, original, and ornamental Design for a Fire Truck, of which the following is a specification, reference being had to the accompanying drawings, forming a part thereof.

In said drawings:

Figure 1 is a side elevational view of a fire truck showing my new design;

Fig. 2 is a top plan view;
Fig. 3 is an elevational view from the front;
Fig. 4 is an elevational view from the rear; and
Fig. 5 is a rear perspective view thereof.

I claim:

The ornamental design for a fire truck, as shown.

JAMES W. FITCH.
